JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

DRAW-BAR CARRY-IRON.

1,074,745.

Specification of Letters Patent.

Patented Oct. 7, 1913.

Application filed April 15, 1912. Serial No. 690,971.

To all whom it may concern:

Be it known that I, JOHN M. ROHLFING, a citizen of the United States, residing at St. Louis, Missouri, have invented a certain new and useful Improvement in Draw-Bar Carry-Irons, of which the following is a full, clear, and exact description, such as will enable others skilled in the art to which it appertains to make and use the same, reference being had to the accompanying drawings, forming part of this specification, in which,—

Figure 1 is a front elevational view of a draw bar carrier of my improved construction with the draw bar shown in vertical section. Fig. 2 is a vertical section taken on the line 2—2 of Fig. 1. Fig. 3 is an enlarged cross sectional view taken approximately on the line 3—3 of Fig. 2.

20 My invention relates to new and improved carrying means for the draw bars of car couplers, the principal objects of my invention being to provide a trussed carrier particularly designed to effectively resist and 25 withstand all pounding movement of the draw bar which ordinarily results in bending of the carrying element and further to provide a carrier with rolling engaging faces, thereby reducing to a minimum the 30 friction between the carrier and the draw bar.

A further object of my invention is to provide a trussed carrier with draw bar supporting rollers that are removable, in 35 order that rollers of different diameters can be utilized for maintaining the draw bar at different heights as is required in practice.

In practice it is essential that the draw 40 bars of cars be properly supported, and in order to permit the cars to round curves and not throw undue strains on the coupler knuckles, it is necessary that proper clearance be provided on each side of the draw bar. In passing over crossings, switches, 45 frogs and the like there is a certain amount of vertical movement imparted to the draw bars, which movement results in severe pounding of the draw bars on the carrying members, and I propose to provide a carrier 50 that is trussed at its center in order to resist this pounding movement of the draw bar.

Ordinary carry irons are provided with

flat top surfaces, and where no centering device for the draw bar is provided, a considerable amount of friction is developed between 55 the underside of the draw-bar and the flat surface of an ordinary carry iron during the return of the draw-bar to a central position, which movement takes place while the cars are moving off from a curve onto a straight 60 portion of a track. Under such conditions the draw-bars are, to a certain degree, pulled outwardly with respect to the cars, thereby bringing into action the draft gear to which the draw-bars are attached, and during this 65 longitudinal movement of the draw-bars they ride lengthwise over the carry irons and at the same time move transversely relative thereto to a central position. By providing one or more rolling supports for the draw- 70 bars the friction between the draw-bars and carriers will be materially reduced during the return of the draw-bars to a central position for the reason that said draw-bars bear upon rolling surfaces during their combined longitudinal and transverse, 75 movements with respect to the carriers.

To the above purposes my invention consists in certain novel features of construction and arrangement of parts hereinafter more 80 fully described and claimed.

Referring by numerals to the accompanying drawings, 1 designates a car end sill, 2 the draft sills and 3 the striking plate, which latter is positioned between and rigidly fixed 85 to the draft sills and end sill.

Formed in the lower portion of the striking plate is an opening 4 adapted to receive the usual draw bar. The lower ends of the portions of the striking plate 3 to the sides 90 of the opening 4 are notched, as designated by 6 in order to receive the ends of the truss member of my improved carrier, and the ears to the sides of these cut away portions are perforated in order to receive a horizontally disposed bolt or rod 7 that forms 95 the main carrying element of my improved device.

The trussing member of my improved carrier comprises a flanged plate 8, preferably 100 T-shaped in cross section, and formed integral with the ends of this plate are lugs 9 that are provided with aligned apertures in order to receive the bolt 7. When the carrier

- is properly assembled these lugs 9 occupy the notches or cut away portions 6 at the lower outer corners of the striking plate. Formed integral with the central portion of the trussing member 8 is a lug 10 having a transverse aperture in alignment with the apertures of the lugs 9 in order to receive the bolt 7. Loosely mounted on the bolt 7 between the lugs 9 and 10 are rollers 11, the 10 diameters of which are such that portions of their peripheries occupy a plane slightly above the plane occupied by the top of the lug 10.
- The bolt or rod 7 is preferably provided 15 on one end with a head and on the opposite end with a nut in order that it may be readily removed when it is desired to change the rollers 11 or remove or repair the draw bar.
- The rollers 11 not only provide a rolling 20 support for the draw bar, but materially reduce the friction between said draw bar and rollers to a minimum during any length-wise movement of the draw-bar with respect to said rollers, thereby enabling the springs 25 of the draft gear to readily return the draw bar to its center position after having been drawn to one side as the cars are rounding a curve or passing from a curve onto straight track. All pounding of the draw bar upon 30 the rollers 11, as a result of the vertical movement of said draw bar while the cars are passing over crossings, switches and frogs and which, under ordinary circumstances, tends to bend the bolt or carrying 35 element is effectively resisted by the trussed carrying element. Interchangeable rollers of different diameters provide simple means for changing the elevation at which the draw bar is carried.
- 40 A carrier of my improved construction is provided with a trussing member that is strongest at its center, thereby permitting the use of a minimum amount of material for maximum strength, and by utilizing rollers for reducing the friction between the carrier and the draw bar during the longitudinal movement of said draw-bar with respect to the carrier, said draw-bar can be easily moved to its normal central position.
- 50 It will be readily understood that minor changes in the size, form and construction of the various parts of my improved carrier can be made and substituted for those herein shown and described without departing from the spirit of my invention.
- I claim:—
1. A drawbar carrier comprising a truss supported transversely beneath the drawbar which truss includes a bolt, and an anti-friction element on said bolt and forming a bearing for the drawbar.
  2. The combination with supports, of a trussed bolt detachably connected to said supports, and an antifriction draw bar engaging member on said trussed bolt.

3. In a draw bar carrier, the combination with a carrying element, of separate trussing means connected thereto and depending therefrom, and anti-friction elements on said carrying element which anti-friction elements are transversely arranged with respect to the draw-bar. 70
4. In a draw bar carrier, the combination with a carrying element, of a separate trussing element therefor provided with spaced bearings, and anti-friction elements between said bearings which anti-friction elements are transversely disposed with respect to the draw-bar. 75
5. In a draw bar carrier, the combination with a carrying element of a separate trussing element and separate anti-friction elements co-operating with said carrying element. 80
6. In a draw bar carrier, the combination with a carrying member, of anti-friction members thereon, the same being transversely disposed relative to the draw-bar, and trussing means carried by said carrying member for reinforcing the central portion 90 of said carrying member. 85
7. The combination with spaced supports on a car body, of a bolt removably positioned in said supports, a trussing member positioned on said bolt between the supports, 95 and anti-friction members on said bolt. 100
8. The combination with a striking plate having depending supporting members, of a bolt removably positioned in said supporting members which bolt is transversely disposed with respect to the carried draw-bar, a trussing element carried by the bolt, and anti-friction rollers mounted on said bolt between the ends of said trussing element. 105
9. In a draw bar carrier, the combination with a carrying element having rolling surfaces, which element is transversely disposed with respect to the carried draw-bar, of a removable trussing element for said carrying element. 110
10. In a draw bar carrier, the combination with a trussed supporting element, of a pair of rollers carried by said element, the same being arranged transversely with respect to the carried draw-bar. 115
11. The combination with supports arranged at the sides of a draw-bar, of a trussed bolt connected to said supports and transversely arranged beneath the draw-bar, and an anti-friction element on said trussed bolt, which anti-friction element is transversely disposed relative to the supported draw-bar. 120
12. In a draw-bar carrier, a trussed bolt transversely disposed beneath the drawbar, 125 and an anti-friction element loosely mounted on said bolt.
13. In a draw-bar carrier, a bolt transversely disposed beneath the draw-bar, a trussing and re-inforcing element mounted 130

on said bolt, and an anti-friction member loosely mounted on said bolt.

14. In a draw-bar carrier, a bolt transversely positioned beneath the draw-bar, a 5 trussing and reinforcing member having a plurality of bearings in which the bolt is seated, and a roller loosely mounted on said bolt.

15. In a draw-bar carrier, a carrying ele- 10 ment, a pair of spaced anti-friction devices

on said element, and a trussed bearing for the carrying element between the anti-friction devices.

In testimony whereof I hereunto affix my signature in the presence of two witnesses, 15 this tenth day of April, 1912.

JOHN M. ROHLFING.
